L. C. MYERS

TYPEWRITING MACHINE

Filed Oct. 18, 1927

UNITED STATES PATENT OFFICE.

LEWIS C. MYERS, OF FREEPORT, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed October 18, 1927. Serial No. 226,952.

This invention relates to improvements intended to be employed on typewriting machines and designed to write Oriental languages, such as Arabic and the like, in which 5 many of the characters require a double space. In the construction shown, all upper case characters have a double space while some lower case characters have a double space and others a single space. The usual 10 stop for the movable dog of the escapement mechanism is set so that ordinarily a double space movement of the carriage occurs whenever a character is written. Certain of the keys, however, operate mechanism which sets 15 an auxiliary stop that limits the movement of the stepping dog to a single space when such keys are depressed. However, the connection by which these keys operate the auxiliary stop is broken when the platen is 20 shifted to upper case position so that all upper case characters have a double space.

The invention is illustrated as applied to a Royal standard machine, although it is applicable to machines of other types. Only so 25 much of the machine is illustrated as is necessary to show the construction and operation of the invention.

In the drawings:

Figure 1 is a fore and aft vertical section 30 with parts in elevation showing the mechanism in normal position.

Figure 2 is a similar view of part of the mechanism shown in operative position.

Figure 3 is a front view of the escapement mechanism.

Figure 4 is a front view of a universal bar.

The drawings disclose a portion of the main frame A, a shift frame B which supports a shaft C carrying a pinion D with which coacts a rack E supported in the usual manner on the carriage. The shaft C also carries an escapement wheel F with which co-operate a rigid dog H and a movable dog K carried by the escapement rocker G. The type action comprises key levers L, each of which is connected by a link M to a front

link N, the free end of which is connected by a link O to the rear end of a type bar P. The link O is connected by another link R 50 to the usual universal bar S in which the escapement mechanism is operated. As illustrated, these parts are such as are usually employed in the Royal machine, but they may be widely varied without departing 55 from the spirit of the invention.

The dog rocker G is provided with a stop 1 which normally limits the movement of the stepping dog to the position *a* shown in dotted lines in Figure 3 and this movement 60 results in a double letter spacing movement of the escapement wheel and consequently of the carriage. It is obvious, therefore, that upon depression of any key lever, the escapement is actuated in the usual manner 65 and a double letter space movement of the carriage will take place unless this is prevented in some manner.

A lever 2 is pivoted at 3 to a bracket carried by the shift frame B, and this lever has 70 an offset end 4 most clearly shown in Figure 3. When this lever is moved, the offset end comes into the path of the movable dog K and limits its stepping movement to the dotted line position *b* shown in Figure 3 75 which permits only a single letter space movement of the escapement wheel and the carriage. A spring 5 which is connected at one end to an ear 6 of the lever 2 and at its other end to a fixed part 7 normally 80 holds the lever 2 in the Figure 1 position.

The lever 2 is moved from the Figure 1 to the Figure 2 position in the following manner. The lower end of this lever 2 is forked and engages over a pin 8 carried by 85 an arm 9 which is pivoted at 10 to a bracket 11 supported by the frame of the machine. This arm is normally held in the Figure 1 position by means of a spring 12 which is connected at one end to the arm 9 and at the other end to an ear 13 on the bracket 11. A bent over ear 14 of the arm 9 contacts with the bracket 11 to limit the movement of the arm under the influence of the spring 12.

and an arm or extension 15 coacts with the bracket 11 to limit the movement of the arm 9 when it is operated.

The arm 9 is operated by means of an adjustable link 16 which is connected thereto at one end and at its other end is connected to an arm 17 which is fast on a rock shaft 18, which rock shaft carries near its ends two forwardly extending arms 19 which support a universal bar 20. This bar has cut-out portions 21 so that certain key levers may be operated without contacting with the bar or producing any movement thereof. It also has a portion 22 with which certain key levers will contact when operated and by such contact will impart movement to the universal bar. Since there are four rows of key levers which extend different distances in front of said universal bar, the contacting portions 22 are arranged at four different elevations as indicated at *c*, *d*, *e* and *f*. This results in a movement of uniform extent being given the universal bar 20 no matter which row of key levers may operate the same. The space bar is supported by levers which contact with the outer projections 23 of the universal bar 20 so that an operation of the space bar when the platen is in lower case position will give a single space movement of the carriage but a double space movement when the platen is in upper case position.

When the parts are in the position shown in Figure 1 and the platen is in lower case position, the depression of any key lever which operates the universal bar 20 will move the stop 4 into operative position as shown in Figure 2 and thus limits the movement of the carriage to a single letter space movement. When the carriage and platen are shifted to upper case position, the lever 2 which is carried by the shift frame will move upward into the dotted line position of Figure 1 and the fork will move out of engagement with the pin 8. When in this position the actuation of any key lever will produce a double space movement of the carriage since even if the universal bar 20 is operated the resultant movement of the arm 9 will be an idle movement producing no effect on the lever 2.

It will be apparent that any desired characters may be given a single space by proper selection of the engaging portions 22 of the universal bar 20. It is also obvious that the change produced by the case shift movement of the carriage is entirely automatic and requires no attention on the part of the operator. The construction by which the result is obtained is very simple and efficient and the mechanism can be embodied in the usual machine without the necessity of making any change in the construction of the regular machine. It is only necessary that the stop 1 shall be normally set to allow the step-

ping dog a double space movement. Various features may be modified without in any way departing from the spirit of the invention which is to be regarded as limited only by the scope of the appended claims.

I claim as my invention:

1. In a typewriting machine having a shift frame and an escapement mechanism including a stepping dog; a stop permitting normal double space movement of said dog, an auxiliary stop, and means for moving said auxiliary stop into position to limit said dog to a single space movement, said means including connections which are disabled when the shift frame is moved to upper case position.

2. In a typewriting machine having key levers, a shift frame, and an escapement mechanism including a stepping dog; a stop permitting normal double space movement of said dog, an auxiliary stop, and means operated by certain of said key levers for moving said auxiliary stop into position to limit said dog to a single space movement, said means including connections which are disabled when the shift frame is moved to upper case position.

3. In a typewriting machine having key levers, a shift frame, and an escapement mechanism including a stepping dog; a stop permitting normal double space movement of said dog, an auxiliary stop, and means operated by certain of said key levers for moving said auxiliary stop into position to limit said dog to a single space movement, said means including connections which are separated when the shift frame is moved to upper case position.

4. In a typewriting machine having a main frame, shift frame, key levers, and an escapement mechanism including a stepping dog; a stop permitting normal double space movement of said dog, an auxiliary stop carried by the shift frame, and means operated by certain of said key levers for moving the auxiliary stop into position to limit the dog to a single space movement.

5. In a typewriting machine having a main frame, shift frame, key levers, and an escapement mechanism including a stepping dog; a stop permitting normal double space movement of said dog, an auxiliary stop carried by the shift frame, and means operated by certain of said key levers for moving the auxiliary stop into position to limit the dog to a single space movement, said means including connections which are disabled when the shift frame is moved to upper case position.

6. In a typewriting machine having a main frame, shift frame, key levers and an escapement mechanism including a stepping dog; a stop permitting normal double space movement of said dog, a lever pivoted on the shift frame, an auxiliary stop carried by

said lever and movable into position to limit said dog to a single space movement, and means operated by certain of said key levers and operatively engaged with said lever.

7. In a typewriting machine having a main frame, shift frame, key levers and an escapement mechanism including a stepping dog; a stop permitting normal double space movement of said dog, a lever pivoted on 10 the shift frame, an auxiliary stop carried by said lever and movable into position to

limit said dog to a single space movement, and means operated by certain of said key levers and operatively engaged with said lever, said means including an arm having 15 a separable connection with said lever, which connection is broken when the shift frame is moved to upper case position.

In testimony whereof, I have hereunto subscribed my name.

LEWIS C. MYERS.
